UNITED STATES PATENT OFFICE.

JOHN O. SCOTT, OF WAUPACA, ASSIGNOR OF TWO-THIRDS TO MYRON F. PATTERSON AND JOHN G. PATTERSON, OF MILWAUKEE, WISCONSIN.

DENTAL ENGINE.

SPECIFICATION forming part of Letters Patent No. 334,985, dated January 26, 1886.

Application filed November 9, 1885. Serial No. 182,232. (No model.)

To all whom it may concern:

Be it known that I, JOHN O. SCOTT, of Waupaca, in the county of Waupaca, and in the State of Wisconsin, have invented certain new and useful Improvements in Dental Engines; and I do hereby declare that the following is a full, clear, and exact description thereof.

My invention relates to dental engines, and will be fully described hereinafter.

3 In the drawings, Figure 1 is a perspective view of my engine complete. Fig. 2 is an elevation, partly in section, of the upper portion of the same. Fig. 3 is a similar view of the lower portion immediately in continuation of Fig. 2. Fig. 4 is a detail of that portion shown in Fig. 3 in a position at right angles to its position in said figure. Fig. 5 is a central vertical section of the upper portion of Fig. 2. Fig. 6 is a horizontal section on the line $x-x$ 20 of Fig. 5. Figs. 7 and 8 are details.

A is the stand of my engine, which may be provided with a supporting base of any desired style. In the top of the stand is fixed a bushing, a, which forms a step for one end of 25 a shaft, B, the upper end of which extends up into a sleeve, C, where it is centered by a bridge, b. This sleeve is seated in or on the upper end of a frame, C', the sides of which project up from the stand A. The shaft B has a collar or enlargement, b', and a spring, B', is confined about the shaft B, between the collar b' and a bridge, c, of the frame C', through which bridge the shaft B passes, the upper end of the spring being secured to shaft B, while the 30 lower end is secured to the bridge c. The spring, therefore, has a torsional action, and its office is to return the shaft B and wind the propelling-cord after each action of the treadle. Near its upper end the frame C' carries a pulley-bracket, C², which forms the bearings for 35 the journals of pulleys C³. The sheaves of the pulleys are arranged diagonally to each other, so that while both ends of the cords D are unwound about the shaft in one direction they 40 will draw from opposite sides of the shaft without interfering. The cord D is passed through the shaft B or otherwise secured to it above the pulley-bracket C², and its ends hang down over the pulleys to the arms e of the 45 treadle E, and the shaft is propelled by de-

pressing the treadle and unwinding the cord, the cord being unwound at each depression of the lever and wound by the torsional action of the spring B' to lift the treadle and prepare for another impulse. The upper end of shaft 55 B is slotted, as at d, to take the pin d' of a coupling, d', by which another shaft, F, is coupled to it, the connection being made by simply dropping shaft F into place. On its upper end shaft F has coupled to it the lower 55 plate, G, of a friction-clutch, the hub g of which has fingers g' to take each a friction-roller, H, which rollers stand upright therein beneath a top plate, j.

K is a cap that fits over the hub and rollers, 65 and this cap carries the axle L of the driving-pulley L'. One end of the axle L extends down into the hub g and fits loosely therein, while the other end has its bearing in a cross-piece, M.

C⁴ is a sleeve that telescopes into sleeve C, 70 and is sustained at a proper height therein by a pin, m, that rests in a notch in the upper rim of sleeve C, and on its upper end the sleeve C⁴ is fitted with a frame that consists of a skeleton or basket, M', that incloses the clutch 75 mechanism, and a cross-bar, M², that with cross-bar M forms the frame of pulley L.

o o' are blocks that separate the cross-bars M and M². The block o is held in place preferably by a single screw-bolt, p, while block o' 80 is held by two screws, p' p', and this last-named block forms the support for the first joint, P, of the tool-arm. This arm does not differ materially from those on other dental engines, consisting merely of jointed arms and 85 a hand-piece connected by pulleys and belts to the driving-pulley.

Just beneath the block o, or at any other convenient point on the cross-bar M², is journaled a mandrel, R, that has a pulley, R', that 90 projects up through a slotted enlargement, m², of the cross-bar M² in such a position that it will be thrown into contact with the under side of the rim of the pulley L' when the sleeve C⁴ is slightly lifted and turned, so as to take 95 the pin m out of its notch in sleeve C, as shown in dotted lines, Fig. 8, and when this is done the mandrel may be used for turning a wheel, S, or any other tool.

While I have shown a peculiar clutch for 100

communicating the motion from shaft B to the pulley L, I do not propose to confine myself to the one shown, but may use any style of clutch I may find desirable.

5 The operation of my device is as follows: When the treadle is in the position shown in Fig. 1, the cord D is wound about the shaft B, and any depression of the treadle will draw the cord off of the shaft B, and in doing so will 10 turn this shaft, which, through its connections, will turn the plate G of the clutch and cause the inclined surfaces between fingers g' to throw the rollers H out against the inner periphery of cap K, and thus give an impulse to 15 the axle L, and then when the shaft B is turned back by the spring B' the hub returns for giving another impulse to the cap, and thus the cap is given successive impulses in one direction, and a very high rate of speed may be 20 attained.

Having now fully described my invention, what I claim as new, and desire to secure by Letters Patent, is—

1. The combination, with a treadle, of a 25 cord leading from the shaft to the arms of the

treadle over suitable pulleys, and a torsion-spring for causing the cord to wind about the shaft, substantially as set forth.

2. The combination of the shaft, cord, treadle, and spring with a clutch, driving-pulley, and 30 connections, as set forth.

3. The combination, with the driving-shaft and driving-pulley, of a clutch consisting of a lower plate having fingered hubs, a cap fitting over the hub, and rollers confined between the 35 sides of the cap and the hub, as set forth.

4. The combination, with the driving-pulley, its frame, and a mandrel and pulley carried by the frame, of the sleeves C and C', and pin for supporting sleeve C' upon sleeve C, 40 substantially as and for the purpose set forth.

In testimony that I claim the foregoing I have hereunto set my hand at Milwaukee, in the county of Milwaukee and State of Wisconsin, in the presence of two witnesses.

JOHN O. SCOTT.
